UNITED STATES PATENT OFFICE

OSCAR A. ROSS, OF NEW YORK, N. Y.

BUILDING CONSTRUCTION

Application filed August 9, 1928. Serial No. 298,445.

This invention relates to building construction and more particularly to that part of building construction known as the door and frame therefor.

At the present time wooden doors are "hung on the job" and owing to the comparatively high cost of not any too efficient labor, such hanging of the doors on the job is comparatively high in cost, and where many such doors are hung, as for example, in "walk up" apartment houses, the cost of an entire unit, or group of units becomes abnormally high.

One of the objects of this invention is to provide a building construction whereby the doors may be hung, or fitted to the frame at the mill in this manner permitting the use of machinery for fitting the door as well as the hinges and locks, said work being done with lower cost labor than if similar work were done at the building construction location. Likewise varnishing, or otherwise finishing the door and frame before shipment to the building construction may be accomplished by low cost labor whereby the doors and frames are assembled and finished as a complete unit before shipment to the building construction.

This invention further provides that the walls of the rooms or passage ways to which the assembled and finished door unit is to be attached may be completely plastered as a finished job whereby after the door and frame assembly is attached, no further finishing of walls will be required.

Other objects and advantages will appear as the description of the invention progresses, and the novel feature of the invention will be pointed out in the appended claims.

This invention consists in the novel construction and arrangement of parts herein-after described, delineated in the accompanying drawings, and particularly pointed out in that portion of this instrument wherein patentable novelty is claimed for certain and peculiar features of the device, it being understood that, within the scope of what herein-after thus is claimed, divers changes in the form, proportions, size and minor details of the structure may be made without departing

from the spirit of, or sacrificing any of the details of the invention.

In describing the invention in detail, reference is had to the accompanying drawing, wherein I have illustrated embodiments of my invention, and, wherein like characters of reference, designate corresponding parts throughout the several views, and in which:

Figure 1 is an elevational view of a false frame erected in a finished wall ready to receive an assembled door frame unit, and, Fig. 2 is a similar view to which an assembled door frame unit has been attached and is ready to receive the moulding, and, Fig. 3 is a sectional view of an assembled door and frame unit completely fitted to a false frame shown in Fig. 1, and is taken on line 3—3 of Fig. 2, and, Fig. 4 is a fragmental sectional view of a modified form of false frame to which has been fitted an assembled door and frame unit of the "Spanish architectural type", and, Fig. 5 is a reduced size view of a boxed or crated assembled door and frame unit taken on line 5—5 of Fig. 6, and Fig. 6 is a similar view taken on line 6—6 of Fig. 5, and Fig. 7 is a fragmental sectional view of another modified form of Spanish type assembly.

Referring to Figs. 1, 2, and 3, plastered wall 1, comprising plaster 2 and laths 4 is supported by studdings 5—5 in known manner.

When the plans are prepared by the architect or builder, the width A and height B for the erection of a false frame, as 6, comprising dressed uprights 7 and capping 8 is given, the width of said uprights and capping or heading being also specified to be that of the thickness of the plastered wall 1 when finished. These dimensions A and B are made sufficiently large whereby when an assembled door and frame unit, as 10 is inserted in false frame 6 to be allocated, a side space, as 11, and a top space, as 12, will occur whereby filler or spacing blocks as 13—13 may be fitted therein for finally allocating said unit, normally this space is preferably not more than one-half inch for the side spaces 11—11 and not more than one inch for the top space 12.

After the assembled door and frame unit 10 has been allocated by filler or spacing blocks,

as 13—13, it is secured by insertion of nails or other fasteners passing through and likewise anchoring said blocks, and thereafter the upright molding strips 14—14 and cap molding 15, as well as corner blocks 16—16 and floor blocks 17—17 are secured in place further acting to rigidly secure said unit in final place.

10 The door and frame unit 10 comprises the door 20, to which has been fitted the lock 21 and hinges 22—22, this fitting being preferably made by machine cuts from jigs at the mill whereby accurately located and clean cuts are made to assure proper fitting of the hardware and satisfactory operating of the doors when the unit is finally allocated.

15 The normal frame 23 comprises the jamb 24, to which the lock strike (not shown) is attached in a machine cut recess, the jamb 25, to which one-half of hinges 22—22 are also preferably attached in machine cut recesses, the top jamb 26a, and the threshold 26, the last named parts, comprising the door frame, being suitably mortised together and after 20 which it is preferably varnished or otherwise finished, whereafter the door 20 is hung on hinges 22—22 and latched in place preferably with the door knobs and spindle therefor removed for separate packaging.

20 30 After the assembled door and frame unit 10 has been assembled as hereinbefore described it is preferably crated or boxed for shipment, as shown in Figs. 5 and 6. Suitable crating, or boxing boards 28—28 being nailed across the frame 23, and if desired the package comprising the door knobs and spindle, may be included in said crate or box, or may be shipped separately.

35 Referring to Fig. 4, showing a modified form of the invention, the false frame 30, is made slightly wider than the width of studdings 5, and the plastering is left incompletely to the edge thereof, and after the assembled door and frame unit 31 has been positioned by filler or spacing blocks 32, a metal lath strip 33 is secured to false frame 30 and said blocks 32, whereafter the rounded plaster portion 34 is added to complete wall 1, usually a rough plaster job. Such construction furnishes a rounded plaster contour dissolving wall 1 into the normal frame unit 31.

40 Referring to Fig. 7, showing another modified form of the invention, the false frame 35, is made of a width substantially that of the studding 5 and the ends of lath 4 are extended to said false frame and the ends thereof beveled. When plastering, the plaster wall 1 is continued to cover the face 36 of said 45 false frame, said plaster being rounded to a radius 37.

45 After the assembled door and frame unit 31 has been allocated by blocks, as 38, a comparatively small molding strip 39 may be added to cover the space 40, or if desired an or-

namental rope or braid, as 41, may be added, either molding, or rope being added to one or both sides as the decoration may require.

50 When a false frame, as, 6, 30, or 35 is erected it may be securely tied to studding 5—5 by spacing blocks, as 3—3, or if the studding is too far distant additional studdings are appropriately placed whereby said false frame may be directly secured thereto without the use of said blocks.

55 It is also preferable to erect a heading, as 5a, for more securely securing the capping 8 of said false frames.

What I claim is:

1. The method of forming a doorway in a 60 wall structure arranged to be plastered, the wall structure having an opening formed therein arranged to act as a passageway therethrough which comprises, erecting an auxiliary frame in the opening and securing the frame to the wall structure, then plastering the wall structure carrying the plastering to the auxiliary frame to form a finished plastered wall, and then erecting a normal door frame in the opening formed in the 65 auxiliary frame, the frames being rigidly secured together to form a rigid portion of the wall structure.

2. The method of forming a doorway in a 70 wall structure arranged to be plastered, the wall structure having an opening formed therein arranged to act as a passageway therethrough, which comprises, erecting an auxiliary frame in the opening and securing the frame to the wall structure, then plastering the wall structure carrying the plastering to the auxiliary frame to form a finished plastered wall, and then erecting a normal door frame in the opening formed by the auxiliary 75 frame, the frames being rigidly spacedly secured together to form a rigid portion of the wall structure.

3. The method of forming a doorway in a 80 wall structure arranged to be plastered, the wall structure having an opening formed therein arranged to act as a passageway therethrough, which comprises, erecting an auxiliary frame in the opening, the edges of the frame being positioned in planes parallel to the surfaces of the wall when plastered, then plastering the wall carrying the plastering to the edges of the auxiliary frame to form a finished plastered wall, and then erecting a normal door frame in the opening formed in the auxiliary frame, the normal frame being secured to the auxiliary frame and positioned relatively thereto whereby the edges thereof will lie in a plane substantially parallel to the wall surfaces.

4. The method of forming a doorway in a 85 plastered wall having studding supporting the plastering, the studding having an opening formed therein arranged to act as the doorway therethrough, which comprises, securing an auxiliary frame in the opening, the 90

frame being secured to the studding and the edges thereof being positioned in a plane substantially parallel to the plane of the surfaces of the wall when plastered, then plastering the wall carrying the plastering to the edges of the auxiliary frame to form a finished plastered wall structure, and then locating a normal door frame in the opening formed by the auxiliary frame, the frames being rigidly secured together to form a rigid portion of the wall structure.

5. The method of forming a doorway in a plastered wall having studding supporting the plastering, the studding having an opening formed therein arranged to act as the doorway therethrough, which comprises, erecting an auxiliary frame in the opening, the frame being secured to the studding and the edges thereof being positioned in a plane substantially parallel to the plane of the surfaces of the wall when plastered, then plastering the wall carrying the plastering to the edges of the auxiliary frame to form a finished plastered wall structure, then spaced-
20 ly allocating a normal door frame in the opening formed by the auxiliary frame, the frames being rigidly secured together whereby the normal frame becomes a rigid portion of the wall structure, and then securing sealing
25 members on each side of the wall adjacent the normal door frame whereby the auxiliary frame and the space between the frames is concealed from view.

6. The method of forming a doorway in a plastered wall having studding supporting the plastering, the studding having an opening formed therein arranged to act as the doorway therethrough, which comprises, erecting an auxiliary frame in the opening, the frame being secured to the studding and the edges thereof being positioned in a plane substantially parallel to the plane of the surfaces of the wall when plastered, then plastering the wall carrying the plastering to the edges of the auxiliary frame to form a finished plastered wall structure, then spaced-
40 ly locating a normal door frame in the opening formed in the auxiliary frame, the frames being spaced relatively by spacing members positioned between the frames whereby a normal space is formed therebetween, and then securing moulding members on each side of the wall engaging the edges of the normal frame whereby the auxiliary frame and the space between the frames are concealed from view.

7. Building structure comprising, a plastered wall having a studding portion for supporting the plastering thereon, an opening formed in the studding thereof forming a passageway through the wall, an auxiliary frame secured to the studding of the opening, the frame having a depth substantially equal to the thickness of the wall when completely plastered and the edges of the frame

extending forwardly and rearwardly of the studding portion whereby the surface of the wall plaster will be substantially parallel therewith to form a finished wall upon completion of the plastering operation, a normal door frame having a door openably supported thereby positioned in the opening formed by the auxiliary frame, the normal door frame having a depth substantially equal to the depth of the auxiliary frame and the edges thereof positioned substantially parallel with the edges of the auxiliary frame, and means for rigidly spacedly securing the frames together whereby the normal frame becomes a rigid part of the wall structure.

8. Building structure comprising, a plastered wall having a studding portion for supporting the plastering thereon, an opening formed in the studding thereof forming a passageway through the wall, an auxiliary frame secured to the studding of the opening, the frame having a depth substantially equal to the thickness of the wall when completely plastered and the edges of the frame extending forwardly and rearwardly of the studding portion whereby the surface of the wall plaster will be substantially parallel therewith to form a finished wall upon the completion of the plastering operation, a normal door frame having a door openably supported thereby positioned in the opening formed by the auxiliary frame, the normal frame having a depth substantially equal to the depth of the auxiliary frame and the edges thereof positioned substantially parallel with the edges of the auxiliary frame, means for rigidly spacedly securing the frames together whereby the normal frame becomes a rigid portion of the wall structure, and moulding members positioned on each side of the wall in juxtaposition to the edges of both of the frames whereby the auxiliary frame and the space between the frames is concealed from view.

9. Building structure comprising, a plastered wall having a studding portion for supporting the plastering thereon, an opening formed in the studding thereof forming a passageway through the wall, an auxiliary frame secured to the studding of the opening, the frame having a depth substantially equal to the thickness of the wall when completely plastered and the edges of the frame extending forwardly and rearwardly of the studding portion whereby the surface of the wall plaster will be substantially parallel therewith to form a finished wall upon the completion of the plastering operation, a normal door frame having a door openably supported thereby positioned in the opening formed by the auxiliary frame, the normal door frame having a depth substantially equal to the depth of the auxiliary frame and the edges thereof positioned substantially parallel with the edges of the auxiliary frame, spacing members positioned in the space be-

tween the frames for locating the normal frame with respect to the auxiliary frame, means for securing the spacing members and the frames together whereby the normal frame becomes a rigid portion of the wall structure, and moulding members secured to each side of the wall having the rearward faces thereof positioned in juxtaposition to the edges of both of the frames whereby the auxiliary frame and the space between the frames is concealed from view.

10. The method of forming a doorway in a wall structure arranged to be plastered, the structure having an opening formed therein arranged to act as a passageway therethrough which involves, erecting an auxiliary frame in the opening, the front and rear edges of the frame being positioned in planes parallel to the front and rear surfaces of the wall when plastered, then plastering the wall, carrying the plastering to the edges of the auxiliary frame to form a finished plastered wall, then erecting a normal door frame in the opening formed in the auxiliary frame, the front and rear edges of the normal frame also being positioned in planes substantially parallel to the front and rear surfaces of the plastered wall, and then securing moulding members to each side of the finished wall, the members engaging the edges of the frames whereby the auxiliary frame is concealed from view.

In testimony whereof I affix my signature.
OSCAR A. ROSS.
